Att'y.

UNITED STATES PATENT OFFICE.

ROBERT E. WILSON, OF CHICAGO, ILLINOIS, ASSIGNOR TO STANDARD OIL COMPANY, OF WHITING, INDIANA, AND CHICAGO, ILLINOIS, A CORPORATION OF INDIANA.

METHOD AND APPARATUS FOR PREVENTING EVAPORATION FROM STORAGE TANKS.

Application filed May 4, 1923. Serial No. 636,589.

The present invention relates to improvements in methods and apparatus for the prevention of the evaporation of stored liquids from storage tanks, and is intended more particularly for use in connection with the storage of such liquids as gasoline, crude petroleum and the like. It will be fully understood from the following description, illustrated by the accompanying drawing, in 10 which;

Fig. 1 is a plan view of a storage tank in connection with which the present invention is employed;

Fig. 2 is a vertical sectional view through 15 the tank illustrated in Fig. 1, and

Fig. 3 is a sectional detail view.

Referring more particularly to the drawings, the numeral 5 indicates a storage tank which may suitably have upright cylindrical walls 6. Within the tank 5 is provided a cover member 7, which may suitably be boat or dish-shaped so as to float upon the surface of the liquid stored within the tank. The cross-sectional dimensions of this floating cover member 7 are somewhat less than those of the interior of the tank, so that the latter is only partially closed by the floating cover 7. Suitable means may be provided to prevent the floating cover 7 from hugging the walls 6 of the tank at any point, for example, spring pressed roller plungers 8. Drain pipes 7^a may likewise be provided to drain through the cover any water that may collect on the surface.

It is readily apparent that in the construction thus described, the surface of the volatile liquid, for example, gasoline, in the tank is only partially covered and evaporation may take place from the uncovered or exposed portion thereof. In order to prevent loss of the vapors evolved from the exposed portion of the surface of the liquid, in accordance with the present invention, I interpose between the exposed surface of the liquid and the atmosphere an expandible septum which is substantially impervious to the vapors evolved from the exposed surface of the liquid. This expandible septum, which is preferably formed of fabric impregnated with a suitable compound, pockets above the exposed surface of the stored liquid the vapors emanating therefrom and prevents their release and diffusion into the atmosphere.

In general it is also desirable to protect 55 the impervious septum thus described from external weather conditions. This may suitably be effected, for example, by employing in connection therewith a similar outer septum or curtain of weatherproof material, 60 for example a waterproofed fabric. If desired, a roof may be provided over the tank.

In the embodiment of the invention illustrated in the drawings, I have shown the protection of the exposed surface of the liquid or gasoline in the storage tank by means of a double curtain 9 extending entirely around the interior of the tank and secured at its upper end by any suitable means, such as the ring 10, to the exterior of the tank and 65 secured at its inner end 11 around or near the periphery of the floating cover 7. The double curtain 9 is of sufficient length to permit the free movement downward of the floating cover 7 on withdrawal of stored liquid without exerting tension on the curtain. 75 The cylindrical curtain 9 completely incloses the exposed surface of the gasoline in the storage tank, forming a closed pocket 12 thereabove. Since the length of the 80 double curtain 9 is sufficient to permit the floating cover 7 to assume a position in the bottom of the tank, I find it advisable to provide means for supporting the slack in the curtain 9 existing when the cover 7 assumes a more elevated position. This may 85 suitably be an annular, trough-like basket 13, secured to the floating cover 7 near its outer margin and extending partly into the pocket 12, and partly into the free space 90 above the floating cover 7. On rise of the floating cover 7, the folds of the curtain fall within this trough-like basket, as illustrated in Fig. 2.

The double curtain 9, is formed as shown 95 more in detail in Fig. 3. The inner ply or layer of the curtain is formed of a material substantially impervious to gasoline vapors, for example, a fabric such as balloon silk thoroughly impregnated with gelatine, together with which may be incorporated small proportions of a hardening agent such as chrome alum, hexamethylenetetramine, formaldehyde, and the like, and a somewhat larger proportion of a softening agent, such as glycerine, and the like. For example, I may form on the curtain a layer containing one part (by weight) glue, two 100 105

parts glycerine and one part water with $\frac{1}{2}$ to $1\frac{1}{2}\%$ of ferrous sulfate. This layer or 5
ply of the curtain, designated by the numeral 14, forms a septum substantially impervious to the vapors arising from the exposed surface of the gasoline and consequently confines or pockets the vapors in the space 12. The outer layer or ply 15 of the curtain 9, that is, the portion exposed 10
to the atmosphere, is substantially impervious to moisture and serves to protect the gasoline-proof septum 14 from exposure to rain or moisture which might injure it, and other atmospheric conditions. This ply or 15
layer 15 may suitably be formed of a fabric, such as balloon silk, impregnated with a suitable waterproofing agent, such as asphalt, paraffin, ceresin, rubber or the like. If desired, separate fabric need not be employed, but a single fabric may be coated on one side with the gelatinous composition and on the other with the waterproofing composition.

Although the present invention has been 25
described in connection with the specific details of means for carrying it into effect, it is not intended that these details shall be regarded as limitations upon the scope of the invention, except in so far as included in 30
the accompanying claims.

I claim:

1. The method of preventing evaporation of stored liquids such as gasoline and the like, which consists in enclosing the space 35
above the exposed surface of such liquids within a flexible septum impervious to such vapors, and interposing between said septum and the atmosphere means for preventing access of moisture to the former.

40 2. The method of preventing evaporation of stored liquids such as gasoline and the like, which consists in enclosing the space above the exposed surface of such liquids within a collapsible and expansible septum 45
impervious to such vapors, and interposing between said septum and the atmosphere means for preventing access of moisture to the former.

3. In apparatus for preventing evaporation of stored liquids such as gasoline, a storage tank at least partially open to the atmosphere, and an expansible septum completely enclosing the exposed surface of the gasoline, said septum comprising an inner 55
gasoline-proof portion and an outer waterproof portion.

4. In apparatus for preventing evaporation of stored liquids such as gasoline, a storage tank, a floating cover within said tank of smaller cross sectional area than the interior thereof, said cover being adapted to float on the surface of the contents of the tank, a curtain secured to the wall of the tank and extending therefrom to the floating cover, said curtain completely en-

closing the uncovered portion of the contents of the tank and being substantially impervious to vapors arising from the liquid in the tank, the curtain permitting relative movement of the floating cover with respect to the wall of the tank.

5. In apparatus for preventing evaporation of stored liquids such as gasoline, a tank, a floating cover within the tank of smaller cross-sectional area than the interior thereof, said cover being adapted to float upon the liquid in the tank, and a flexible curtain extending from the floating cover to the wall of the tank and completely enclosing the exposed portion of the liquid in the tank, said cover comprising an inner portion impervious to the vapors arising from the liquid in the tank and an outer substantially waterproof portion.

6. In apparatus for preventing the evaporation of stored liquids, a storage tank, a floating cover within said tank and of smaller cross sectional area than the interior thereof, said cover being adapted to float on the liquid in the tank, and a curtain secured around the upper margin of the tank on the one hand and approximately around the margin of the cover on the other hand, said curtain being substantially impervious to the vapors arising from the liquid in the tank and completely enclosing the exposed portion thereof.

7. In apparatus for preventing the evaporation of stored liquids, a storage tank, a floating cover within said tank of less cross-sectional area than the interior thereof, said cover being adapted to float on the liquid in the tank, and a curtain secured to the upper margin of the tank on the one hand and approximately to the outer periphery of the floating cover on the other hand, said curtain comprising an inner portion substantially impervious to vapors arising from the liquid in the tank and an outer portion substantially impervious to water.

8. In apparatus for preventing the evaporation of stored liquids, a storage tank, a cover within said tank of smaller cross-sectional area than the interior thereof, said cover being adapted to float on the surface of the liquid in the tank, a curtain secured to the margin of the tank on the one hand and to approximately the periphery of the floating cover on the other hand, said curtain being substantially impervious to vapors arising from the liquid in the tank and being of sufficient length to permit the floating cover to assume a low position in said tank, and means for supporting the excess portion of the curtain on rise of the floating cover.

9. In apparatus for preventing the evaporation of stored liquids, a storage tank, a cover within said tank of smaller cross-sectional area than the interior thereof, said

cover being adapted to float on the surface of the liquid in the tank, a curtain secured to the margin of the tank on the one hand and to approximately the periphery of the floating cover on the other hand, said curtain being substantially impervious to vapors arising from the liquid in the tank and being of sufficient length to permit the floating cover to assume a low position in said tank, and trough-like means secured to the floating cover for supporting the curtain on rise of said cover.

ROBERT E. WILSON.
